Heedong Chae(57) **CLAIM**

The ornamental design for a case for electronic device, as shown and described.

DESCRIPTION

FIG. 1 is a front perspective view of a case for electronic device, comprised of inner portion, outer portion, and support leg, showing my new design in an assembled state; FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view thereof, showing the support leg in an open position;

FIG. 10 is another rear perspective view thereof;

FIG. 11 is an exploded rear perspective view thereof showing the inner portion, outer portion, and support leg of the case for electronic device separated for clarity of disclosure;

FIG. 12 is a front perspective view of the inner portion only shown separately for clarity of disclosure;

FIG. 13 is a rear perspective view thereof;

FIG. 14 is a front perspective view of the support leg only shown separately for clarity of disclosure;

FIG. 15 is a rear perspective view thereof;

FIG. 16 is a front perspective view of the outer portion only shown separately for clarity of disclosure; and,

FIG. 17 is a rear perspective view thereof.

The broken line showing of environment is for illustrative purposes only and forms no part of the claimed design.
